DESIGN FOR A BOTTLE

Rudolph P. Kunett, West Hartford, Conn., assignor to G. F. Heublein & Bro. Inc., Hartford, Conn., a corporation of Connecticut

Application February 1, 1945, Serial No. 117,709

Term of patent 14 years

(Cl. D58—8)

To all whom it may concern:

Be it known that I, Rudolph P. Kunett, a citizen of the United States, residing at West Hartford, in the county of Hartford and State of Connecticut, have invented a new, original, and ornamental Design for a Bottle, of which the following is a specification, reference being had to the accompanying drawing, forming part thereof.

In the drawing

Fig. 1 is a front elevational view of a bottle showing my new design;

Fig. 2 is a rear elevational view of the same; Fig. 3 is a sectional view on the line 3—3 of Fig. 1;

Fig. 4 is a sectional view on the line 4—4 of Fig. 1; and

Fig. 5 is a bottom plan view.

I claim:

The ornamental design for a bottle, substantially as shown.

RUDOLPH P. KUNETT.
